US0D1045498S

(12) United States Design Patent (10) Patent No.: US D1,045,498 S
(45) Date of Patent:  Oct. 8, 2024

(54) COOKING POT

(71) Applicant: Fissler GmbH, Idar Oberstein (DE)

(72) Inventors: Tim Konetzka, Augsburg (DE); Sven Feustel, Stuttgart (DE)

() Term: 15 Years

(21) Appl. No.: 35/516,559

(22) Filed: Jan. 31, 2023

(80) Hague Agreement Data

Int. Filing Date: Jan. 31, 2023

Int. Reg. No.: DM/227224

Int. Reg. Date: Jan. 31, 2023

Int. Reg. Pub. Date: Mar. 10, 2023

(51) LOC (14) Cl. 07-02

(52) U.S. Cl.

USPC D7/394; D7/391

(58) Field of Classification Search
